UNITED STATES PATENT OFFICE.

OTTO PETERMANN, OF GROTON, NEW YORK, ASSIGNOR TO CORONA TYPEWRITER COMPANY, INCORPORATED, A CORPORATION OF NEW YORK.

RIBBON MECHANISM FOR TYPE-WRITING MACHINES.

1,121,038.

Specification of Letters Patent.

Patented Dec. 15, 1914.

Application filed October 25, 1910, Serial No. 589,052. Renewed October 8, 1914. Serial No. 865,775.

To all whom it may concern:

Be it known that I, OTTO PETERMANN, a citizen of the Republic of Switzerland, and a resident of Groton, county of Tompkins, 5 and State of New York, have invented certain new and useful Improvements in Ribbon Mechanism for Type-Writing Machines, of which the following is a full, clear, and exact description.

10 This invention relates more particularly to ribbon spool-operating means of what are known as front-strike typewriting machines.

In certain of my pending applications, the 15 ribbon spools have been mounted upon a foldable or shiftable portion of the frame which may be moved into compact relation to another part of the machine with the platen or platen carriage, and the ribbon spools have been so mounted upon the frame that to wind the ribbon from one 20 spool on to another it required the tightening of one thumb nut and the releasing of another to cause one spool to be positively 25 rotated and the other to remain free to rotate on its support. In this case, a part of the ribbon mechanism was operated continuously and the movement of the ribbon in one direction or the other depended upon 30 the tightening of one thumb nut and the loosening of the other, but very often the operator would either permit both thumb screws to be loose so that the ribbon did not move and which would result in bad printing, 35 or possibly make a hole in the ribbon, or the operator would tighten one spool and forget to release the other, thus causing a strain on the ribbon mechanism and very often destroying the alinement as well as 40 injuriously affecting other parts of the construction.

The primary object of the invention is to 45 overcome the objections referred to and to provide means whereby it will not be necessary to tighten the parts so that one spool will be positively operated and the other rotated freely on its support, and to provide means whereby the ribbon spool mechanism may be easily and readily disengaged 50 from one spool and caused to engage the other spool so that only one spool is operated as the keys are moved thus giving

a step-by-step movement to the ribbon without any liability of both spools being positively operated by the mechanism at the 55 same time.

Another object of the invention is to provide simple and efficient ribbon reversing mechanism which may be folded with the platen into compact relation to another part 60 of the machine when not in use.

Other objects of the invention are to provide simple and efficient mechanism in which pawls are employed for rotating the ribbon spools, and to provide simple means 65 which will throw one set of pawls out of engagement with one spool and place the other set of pawls in engagement with the other spool.

A further object of the invention is to 70 provide a ribbon shift mechanism including a transversely arranged bar located adjacent to the platen and which bar may be moved from opposite sides of the machine to cause the ribbon to move in either direction. 75

A still further object of the invention is to provide simple and efficient means which may be operated in connection with a part of the escapement operating mechanism in 80 order that at each depression of a key one of the spools may be operated so as to impart a step-by-step movement to the ribbon.

With these and other objects in view, the 85 invention will be hereinafter more particularly described with reference to the accompanying drawings, which form a part of this specification, and will then be pointed out in the claims at the end of the description. 90

In the drawings, Figure 1 is a longitudinal section, partly in elevation, of one form of typewriting machine embodying my invention. Fig. 2 is a detail plan view of the platen and ribbon operating mechanism. 95 Fig. 3 is an enlarged fragmentary view of one end of the ribbon mechanism, showing the same in an inoperative position; and Fig. 4 is a fragmentary detail view of one end of the shift bar.

The machine frame 10 may have a plurality of transversely-extending rods 11 on which are pivotally mounted the key-levers 12. These key-levers may be forced in one 100

direction by the springs 13, and each key-lever at its inner end may be connected by a link 14 to one of the type-bars 15. These type-bars are pivoted at one end to the brackets 16 and the other ends are provided with type-heads 17 having a plurality of characters thereon which are adapted to be forced against the platen 18. The platen 18 is mounted upon a carriage 19 which is 5 adapted to travel back and forth along a bed 20, the latter being held to a suitable support 21, and said support is pivoted at 22 to arms 23 on opposite sides of the machine so that the platen carriage and parts 10 mounted thereon may be moved into overhanging relation to the keyboard or type-bars. The arms 23 are held to slides 24, one at each rear corner of the machine, and connected to the slides 24 is a suitable shift 15 mechanism for elevating the platen and carriage. The parts thus far described may be 20 of any suitable form and constructed in any desired way.

The transversely-extending bar 26 is 25 located between the slides 24 and may be connected to two upright arms or levers 27 which may be pivoted at their ends to a transversely-extending rod 28 so as to rock thereon, and said arms 27 have vertical slots, 30 as 29, which are engaged by the inturned ends 30 of bell-crank levers 31. There are two arms 27 and two bell-crank levers which are pivoted to a part of the frame adjacent to the arms 27 and have their outer ends, as 35 32, connected by upright portions 33 of a universal bar 34. This bar 34 is located over the key-levers and the space-bar levers in the usual manner, and as each lever is depressed, the universal bar will be raised and 40 will cause the arms 27 on the rod 28 to rock back and forth, said arms together with the bar 26 serving as a frame and as a part of the feed mechanism.

A plate or device 35 is secured at or near 45 each end of the transversely-extending and rocking bar 26, and this plate 35 may be adjustably held to said bar 26 by a slot and a screw 36, and the outer end of each of said plates 35 is upturned, as at 36^a, and is 50 adapted to rock or move back and forth with the arms 27 and bar 26. At each side of the machine and secured to the arms 21 and to the upturned flange 38 of the carriage bed, is a plate 37, or this may be otherwise 55 arranged and constructed from that shown. There are two plates 37 and each may form a part of the foldable support, and pivoted at 39 is a bell-crank lever 40. There are two bell-crank levers one at each 60 side of the machine, and one arm, as the arm 41, is bent inwardly and downwardly and is adapted to be moved into the path of the upturned end 36^a of one of the devices 35 in order that when the frame is rocked, 65 the bell-crank lever will be also moved on

its pivot, provided the arm 41 is in the path of movement of said end 36^a. Each bell-crank lever has a rearwardly-extending arm 42, and pivoted to this arm at 42^a is a pawl 43. The pawl 43 has a part 44 adapted to 70 engage the teeth of one of the ratchet wheels 45 and each wheel is rotatably held on a spindle 46, and movable with each ratchet wheel is a ribbon spool 47, said ribbon spools and ratchet wheels being loosely mounted to 75 rotate on said spindles 46. A dog or detent 48 is pivoted at 49 to each plate 37, and this dog has a part 50 adapted to engage the teeth of the ratchet wheel 45 and prevent the rotation of the same except in one direction. The pawl 43 is normally forced into engagement with the ratchet wheel by means of a spring 51, one end of which engages the arm 42 and the other the pawl 43, while the pawl or dog 48 is normally 80 forced into engaging position by a spring 52, one end of which is held to the plate 37, and the other end to the dog. The dog 48 has a substantially V-shaped recess in its outer end forming the engaging part 50 and a cam part 53, and this cam part is adapted to be engaged by the end 54 of the pawl 43 when the bell-crank lever is moved in one direction and to be disengaged therefrom when moved in the opposite direction, as 85 will be presently described, there being a spring 55 one for each bell-crank lever, one end of which spring is fastened to a projecting part 56 on the bell-crank lever, and its other end to an upwardly-projecting 90 part or lug 57 on each plate 37 and tending to force the arm 41 of the bell-crank lever in the path of the end 36^a of one of the devices 36.

To move the bell-crank levers in such a 105 way as to release the pawls from one ratchet wheel and to permit the pawls of the other ratchet wheel to engage the same, various means may be employed. As shown, a bar, element or member 58 is provided, and this 110 bar extends transversely of the machine along the flange 38 of the carriage bed and in front of the same, and at opposite ends thereof is provided with a finger portion 59 by which the said bar may be forced with a 115 sliding movement transversely of the machine from either side thereof. A slot 60 is provided at or near each end of the bar 58 and through this slot passes a screw 61 one end of which engages a projecting part 62 of the plate 37 and the flange 38 of the carriage bed, and the head of said screw at each end of the machine serves as a guide for the bar and the body of said screw serves to limit the movement of said bar. The bar 120 at its lower edge is provided with two cut-away parts or slots 63, Fig. 4, and adapted to enter each slot is the outer end of the arm 42 of the bell-crank lever or pawl-carrying element, said slots being somewhat larger 125 130

than the end of the arm 42. As will be seen when the bar is forced in one direction, as for example that shown in Fig. 2, the bell-crank levers will be forced so that the arm 41 on the right will be in the path of the movement of the upturned end 36^a of the plate or device 35, while the arm of the bell-crank lever on the left side will be carried out of the path of movement of said device 10 on that side. During such movement, the end 54 of the pawl 43 will pass along and be guided by the upwardly-projecting portion or lug 57 and will enter the V-shaped recess in the end of the holding dog or detent 48, and during this movement the said pawl 43 will be disengaged from the ratchet wheel 45 and the action of the pawl 43 on the dog 48 will also disengage the same from the ratchet wheel so that the ribbon spool and 20 the ratchet wheel on that side of the machine may move freely on its spindle 46. At the same time that the pawls 43 and 48 are released from one ratchet wheel, the same movement causes the two pawls on the other 25 side of the machine to be forced by their springs into engagement with the ratchet wheel of the ribbon spool, and at the same time causes the arm 41 of the bell-crank lever at that side of the machine to be positioned in the path of movement of the upturned end 36^a of the plate 35 of that side of the machine. It will, therefore, be seen that as each key-lever is depressed, the rocking of the arms 27 will cause a movement to be 30 imparted to one of the bell-crank levers only and this will impart a step-by-step movement to the ribbon and as soon as the ribbon has been moved sufficiently to be wound from one spool on to the other, the bar 58 may be then moved or shifted in an opposite direction, and this will release the pawls from the ratchet of the full spool and cause the pawls on the opposite side to operate the ribbon spool to wind the ribbon thereon. 40 This operation will continue until the bar is again forced in the opposite direction. 45 A flat spring 64 is secured at one end of the flange 38 of the carriage bed, and this spring has its free end, as 65, adapted to engage the inner surface of the bar 58 in order to exert tension on the same and prevent the bar from shifting too easily. The bar 58 is provided with a slot or groove adapted to be engaged by the end of the spring when 50 the bar is moved in one direction tending to hold it against accidental movement, and said end of the spring is adapted to enter the opening or slot 60 of the bar when the latter is moved in the opposite direction. 55 By this means, the bar must be given a positive movement before the pawls or ribbon mechanism can be disengaged from one spool and placed into engagement with the other. 60 65 It will be understood that the word "en-

tire" as employed in certain of the claims and as applied to the immediate operating mechanism for each spool is intended to include those parts which directly coöperate with the ratchet wheel or other element, as 70 the pawls and the means on which the actuating pawl is mounted, or the equivalent thereof, and when it is stated in certain of the claims that the "mechanism" of one of the spools is active or inactive, it is intended that the parts referred to or the equivalent thereof are in this condition. The construction shown is such that when either spool is being positively driven the actuating pawl of the other spool and the part on which 75 this pawl is mounted are not moved at all and both pawls of each spool at this time are out of engagement with the ratchet wheel.

From the foregoing, it will be seen that 80 simple and efficient mechanism is provided whereby the direction of movement of the ribbon may be easily and quickly changed so as to cause the ribbon to move with a step-by-step movement first in one direction and 85 then in the opposite direction; that said mechanism may be applied to various kinds of machines whether of the folding type or other make; that said mechanism may be readily and cheaply made and assembled; 90 and that simple means is provided for operating the ribbon spools and which may be also employed to operate the escapement mechanism.

Having thus described my invention, I 100 claim as new and desire to secure by Letters Patent:—

1. In a typewriting machine, the combination with key-levers and type-bars operated by said key-levers, of a platen normally in 105 the path of the type-bars and shiftable into compact relation to another part of the typewriter when not in use, a support shiftable with the platen, a plurality of ribbon spools independently rotatable on said support and 110 foldable with the platen, independent mechanism located on opposite sides of the machine and adapted to independently rotate the ribbon spools, and means mounted on the support for simultaneously disengaging the 115 mechanism from one of the spools and causing the mechanism of the other spool to engage the same to rotate said spool.

2. In a typewriting machine, the combination with key-levers and type-bars operated 120 by said key-levers, of a carriage, a platen mounted on the carriage and normally in the path of the type-bars and shiftable with the carriage into compact relation to another part of the typewriter when not in use, a 125 plurality of ribbon spools foldable with the platen, mechanisms located on opposite sides of the machine and adapted to independently rotate the ribbon spools, and means shiftable with the carriage in its compact 130

movement for simultaneously actuating a part of said mechanisms to cause one spool to be positively rotated and another spool to rotate freely independent of the operating mechanism.

3. In a typewriting machine, the combination with key-levers and type-bars operated by said key-levers, of a carriage, a platen mounted on the carriage and normally in 10 the path of the type-bars and shiftable into overhanging relation to the keyboard of the typewriter when not in use, a support, two ribbon spools independently rotatable on said support and foldable with the platen 15 and carriage, independent mechanisms located on opposite sides of the machine and adapted to rotate the ribbon spools, and a movable bar for simultaneously actuating said mechanisms to cause one spool to be 20 positively rotated and the other spool to rotate freely on its support.

4. In a typewriting machine, the combination of a support, a plurality of spools adapted to rotate on said support, independent means including a horizontally arranged bell crank lever for rotating each spool, and a slidably held bar movable transversely of the machine and having slots near its ends adapted to fit over one arm of each 30 bell-crank lever of the spool-operating means to throw one means out of engagement with one spool and to throw the other means into engagement with the other spool.

5. In a typewriting machine, the combination of a support, two spindles located on opposite sides of the machine and held to the support, spools rotatably mounted on the spindles, a ratchet wheel carried by each spool, a bell-crank lever pivotally held adjacent to said ratchet wheel, a pawl mounted 40 on said lever and adapted to engage the ratchet wheel, a holding dog, key-levers, a rocking bar operatively connected to be moved by the key-levers, means carried by 45 the bar adapted to operate the bell-crank levers, and means for operating the bell-crank levers whereby one of said levers is moved into the path of said rocking bar and the other lever moved out of the path therefore 50 of to cause one spool to be positively rotated and allow the other spool to move freely on its spindle.

6. In a typewriting machine, the combination of a support, a plurality of rotatable spools mounted on said support, two independent ratchet wheels for operating the spools, a bell-crank lever pivotally held adjacent to each ratchet wheel, means moved by said lever and adapted to rotate the 55 ratchet wheel, key-levers, a rocking bar operatively connected to be moved by the key-levers, projecting means carried by the bar adapted to operate the bell-crank levers, and a slidably held and transversely movable

device for shifting the bell-crank levers for 65 the purpose set forth.

7. In a typewriting machine, the combination of a support, a plurality of spools mounted on the support, a ratchet wheel carried by each spool, a horizontally movable bell-crank lever pivotally held adjacent to said ratchet wheel away from the axis of the spool, a pawl mounted on said lever and adapted to engage the ratchet wheel, a holding dog, key-levers, a rocking bar operatively 70 connected to be moved by the key-levers, and means carried by the bar adapted to independently operate the bell-crank levers.

8. In a typewriting machine, the combination of a support, a plurality of spools rotatably mounted on the support on opposite sides of the machine, ratchet wheels for operating the spools, key-levers, a rocking frame comprising vertically arranged arms 85 and a transversely-extending bar and operatively connected to be moved by the key-levers, and independent means movable by the frame adapted to rotate the ratchet wheels, only one of said means being actuated at a time.

9. In a typewriting machine, the combination of a support, two spools held to said support on opposite sides of the machine, key-levers, a rocking bar operatively 95 connected to the key-levers to be moved by the same, devices projecting outwardly from the rocking bar, independent mechanisms operated by said devices and adapted to rotate the spools independently of each other, 100 said mechanisms being operated one at a time only, and means for disengaging one mechanism from one spool and causing the other mechanism to engage with the other spool.

10. In a typewriting machine, the combination of a support, two spools held to said support on opposite sides of the machine, key-levers, a rocking frame comprising upwardly-extending arms and a bar connecting 110 said arms, said arms being operatively connected to the key-levers to be moved by the same, adjustably held devices projecting outwardly from the frame, independent mechanisms operated by said devices one at a time 115 and adapted to rotate the spools independently of each other, and a transversely-extending and slidably element for disengaging one mechanism from one spool and causing the other mechanism to engage with and 120 operate the other spool.

11. In a typewriting machine, the combination of a support, two ribbon spools rotatably held on the support on opposite sides of the machine, key-levers, devices located 125 on opposite sides of the machine and moved by the key-levers, and independent movable arms carrying pawls and operated by said

devices one at a time and adapted to rotate the spools independently of each other.

12. In a typewriting machine, the combination of a support, two spools held to said support on opposite sides of the machine, key-levers, devices located on opposite sides of the machine, horizontally movable bell-crank levers operated by said devices and having means adapted to rotate the spools independently of each other, only one of said levers being operated at a time, and a sliding bar embracing the bell-crank levers for disengaging one bell-crank lever from one spool and causing the other bell-crank lever to rotate the other spool.
13. In a typewriting machine, the combination of a support, two spools mounted on the support at opposite sides of the machine, a ratchet wheel movable with each spool, a bell-crank lever for each ratchet wheel having an inwardly and downwardly projecting arm, key-levers, a rocking bar operatively connected to be moved by each key-lever, devices carried by the rocking bar adapted to engage one only of the bell-crank levers at a time, a pawl carried by each bell-crank lever, a holding dog adapted to engage each ratchet wheel and adapted to be disengaged therefrom by the pawl of the bell-crank lever, and a sliding bar movable transversely of the machine and having finger portions, said bar engaging a part of each bell-crank lever and moving the same therewith, and a spring normally forcing each bell-crank lever in one direction.

14. In a typewriting machine, the combination of a support, ribbon supporting means mounted on the support, a ratchet wheel, a horizontally movable bell-crank lever having an inwardly projecting arm, key-levers, a rocking frame operatively connected to be moved by each key-lever, devices carried by the frame adapted to engage the bell-crank levers to operate one only at a time, a pawl carried by each bell-crank lever, and a holding dog for each ratchet wheel.

15. In a typewriting machine, the combination of a support, two spools mounted on the support at opposite sides of the machine, a ratchet wheel carried by each spool, a bell-crank lever having an inwardly-projecting arm, key-levers, a rocking frame operatively connected to be moved by each key-lever, devices carried by the rocking frame adapted to engage one of the bell-crank levers at a time, a spring-actuated pawl carried by each bell-crank lever, a spring-actuated holding dog adapted to engage each ratchet wheel and adapted to be disengaged therefrom by the pawl of the bell-crank lever, and a sliding bar movable transversely of the machine and having finger portions at the ends of said bar, said bar loosely engaging a part of each bell-crank lever and moving the same

therewith, and a spring normally forcing each bell-crank lever in one direction.

16. In a typewriting machine, the combination of a support, two spools mounted on opposite sides of the machine, a plate for each spool forming a part of the support and having a projection extending upwardly therefrom, a ratchet wheel movable with each spool and rotatably held to the plate, a bell-crank lever pivotally held to the plate and having one arm extending inwardly and downwardly and the other arm rearwardly, a spring-pressed pawl carried by the rear arm of each lever and having an engaging end adapted to engage the projection and be guided thereby, a spring normally forcing the bell-crank lever in one direction, a spring-pressed holding dog having a V-shaped recess adapted to be engaged by the pawl to release said dog from engagement with the ratchet wheel when moved in one direction, a bar having a finger portion at each end and held to slide transversely of the machine and having slots engaging the rearward arm of each bell-crank lever to move the same therewith to cause one set of pawls to engage the ratchet wheel of one spool, and to disengage the other pawls from the ratchet wheel of the other spool, and a tension spring engaging the bar and tending normally to hold it against accidental movement.

17. In a typewriting machine, the combination of a support, two spools mounted on opposite sides of the machine, a projection extending upwardly from the support on opposite sides of the machine, a ratchet wheel movable with each spool and rotatably held on the support, a bell-crank lever pivotally held to the support and having one arm extending inwardly and the other arm rearwardly, a spring-pressed pawl carried by the rearward arm of each lever and having an engaging end adapted to engage the projection and be guided thereby, a spring normally forcing the bell-crank lever in one direction, a spring-pressed holding dog having a V-shaped recess adapted to be engaged by the pawl to release the same from engagement with the ratchet wheel when moved in one direction, and a bar having a finger portion at each end and held to slide transversely of the machine and having slots engaging the rearward arm of each bell-crank lever to move the same therewith to cause one set of pawls to engage the ratchet wheel of one spool, and to disengage the other pawls from the ratchet wheel of the other spool.

18. In a typewriting machine, the combination of a support, two spools mounted on opposite sides of the machine, a ratchet wheel movable with each spool and rotatably held on the support, a bell-crank le-

- ver pivotally held to the plate and having one arm extending inwardly and the other arm rearwardly, a spring-pressed pawl carried by the rearward arm of each lever and 5 having an engaging end, a spring normally forcing the bell-crank lever in one direction, a spring-pressed holding dog adapted to be engaged by the pawl to release the same from engagement with the ratchet wheel 10 when moved in one direction, and a bar having a finger portion at each end and held to slide transversely of the machine and having slots engaging the rearward arm of each bell-crank lever to move the same there- 15 with to cause one set of pawls to engage the ratchet wheel of one spool, and to disengage the other pawls from the ratchet wheel of the other spool.

19. In a typewriting machine, the combination of a support, two spindles located on opposite sides of the machine and held to the support, spools rotatably mounted on the spindles, a ratchet wheel carried by each spool, a bell-crank lever pivotally held adjacent to said ratchet wheel, a pawl mounted on said lever and adapted to engage the ratchet wheel, a holding dog, key-operated levers, a rocking bar operatively connected to be moved by the key-operated levers, 20 means carried by the bar adapted to operate the bell-crank levers, and means for operating the bell-crank levers whereby one of said levers is moved into the path of said rocking bar and the other moved out of the 25 path thereof to cause one spool to be positively rotated and the other caused to move freely on its spindle, said dogs being automatically disengaged from the ratchet wheels by engagement with the pawls during their disengaging movement.

20. In a typewriting machine, the combination of a support, two spools mounted on the support at opposite sides of the machine, a ratchet wheel movable with each spool, a bell-crank lever for each ratchet wheel having an inwardly and downwardly projecting arm, key-levers, a rocking bar operatively connected to be moved by each key-lever, devices carried by the rocking bar 45 adapted to engage one only of the bell-crank levers at a time, a pawl carried by each bell-crank lever, a holding dog adapted to engage each ratchet wheel and adapted to be disengaged therefrom by the pawl 50 of the bell-crank lever, and manually operated means for operating the bell-crank levers to move the pawls to an engaged or disengaged position.

21. In a typewriting machine, the combination of a support, two spools mounted on opposite sides of the machine on said support, a ratchet wheel carried by each spool, a bell-crank lever for each spool, a pawl mounted on each bell-crank lever adapted to

engage its coöperating ratchet wheel, a holding dog for each ratchet wheel adapted to be engaged by the pawl located adjacent thereto when the bell-crank is moved in one direction to disengage the pawl from the ratchet wheel, and means for operating the 70 bell-crank levers one at a time.

22. In a typewriting machine, the combination of a support, two spools mounted on opposite sides of the machine on said support, ratchet wheels carried by the spools, 75 a lever for each spool, means for operating the levers, pawls mounted on said levers adapted to engage the ratchet wheels, and normally fixed holding dogs adapted to be engaged by the pawls and automatically 80 disengaged from the ratchet wheels when the pawls are moved to a disengaged position.

23. In a typewriting machine, the combination of a support, a rocking frame, two 85 ribbon spools, mechanisms for independently rotating the spools, and means for throwing one entire mechanism into operative relation with the rocking frame and the other entire mechanism out of operative relation 90 thereto.

24. In a typewriting machine, the combination of a support, a rocking frame, two ribbon spools, mechanisms for independently rotating the spools, a bar for throwing 95 one entire mechanism into operative relation with the rocking frame and the other mechanism out of operative relation thereto.

25. In a typewriting machine, the combination of a support, a movable frame, two 100 ribbon spools, mechanisms for independently rotating the spools, and a manually operated and transversely-extending bar for throwing one entire mechanism into operative relation with said frame and the other 105 entire mechanism entirely out of operative relation thereto.

26. In a typewriting machine, the combination of a support, a rocking frame having outwardly extending portions, two ribbon spools mounted upon said support, holding dogs, a bell-crank lever for each spool, a pawl mounted on each lever adapted to rotate one of said spools, and a bar slid- 110 ily held on the support and adapted to move one bell-crank into the path of movement of the projecting portion of the rocking frame and the other out of operative relation thereto.

27. In a typewriting machine, the combination of a support, a movable frame having outwardly extending portions, two ribbon spools mounted upon said support, holding dogs, a bell-crank lever for each spool carrying a pawl adapted to rotate said 115 spools, and means slidably held on the support and adapted to move one bell-crank into the path of movement of said portion 120 125

of the frame and the other out of operative relation thereto.

28. In a typewriting machine, the combination of a support, a platen carriage arranged on said support and shiftable into compact relation to another part of the machine when not in use to make the same occupy less space than when in a normal working position, ribbon mechanism including 10 pawl-carrying bell-crank levers located on opposite sides of the machine, a rocking frame having projecting portions independent of the bell-crank levers and separable from the bell-crank levers, said levers and 15 ribbon mechanism being shiftable with the carriage in its compact movement, means for throwing one bell-crank lever into operative relation and the other out of operative relation with the rocking frame, and 20 means for operating the rocking frame.
29. In a typewriting machine, the combination of a support, a platen carriage arranged on said support and shiftable into compact relation to another part of the machine when not in use to make the same occupy less space than when in a normal working position, ribbon mechanism including 25 pawl-carrying bell-crank levers located on opposite sides of the machine, key-operated levers, and mechanism operated by said key-operated levers and separable from the bell-crank levers, said levers and ribbon mechanism being shiftable with the carriage in 30 its compact movement.
30. In a typewriting machine, the combination of a support, two ribbon spools mounted thereon, independent means for independently rotating the ribbon spools, key-operated levers, and means for throwing one 35 only of the entire spool-operating means into operative relation to the key-operated levers.

31. In a typewriting machine, the combination of a support, key-operated levers, ribbon spools mounted on said support, 40 mechanisms for independently rotating the 45

ribbon spools only one of the entire mechanisms being in operative relation with said levers at the same time.

32. In a typewriting machine, the combination of a support, two ribbon spools located at a distance apart, mechanism for each of the spools adapted to independently rotate the same, means for throwing one mechanism into position to operate one spool and the other out of operative position, key-operated levers, and means whereby one ribbon mechanism may remain entirely inactive of any movement by said levers.

33. In a typewriting machine, the combination of a support, two ribbon spools located at a distance apart, a mechanism for each of the spools adapted to independently rotate the same, a bar for throwing one mechanism into position to operate one 65 spool and the other out of operative position, key-operated levers, and means whereby one entire mechanism may be thrown into operative relation to the key-operated levers and the other entirely out of operative 70 relation thereto.

34. In a typewriting machine, the combination of a support, ribbon spools located at a distance apart, mechanism for each of the spools adapted to independently 75 rotate the same, a bar for throwing one mechanism into position to operate one spool and the other out of operative position, key-operated levers, and means separable from the ribbon mechanisms whereby 80 one entire mechanism may be thrown into operative relation with the key-operated levers and the other entire mechanism out of operative relation thereto.

This specification signed and witnessed 85 this 22d day of October A. D. 1910.

OTTO PETERMANN.
